NORVIN J. STEINAU, OF LOUISVILLE, KENTUCKY, ASSIGNOR TO THE STEINAU COMPANY, OF LOUISVILLE, KENTUCKY, A COPARTNERSHIP CONSISTING OF NORVIN J. STEINAU AND LESLIE S. STEINAU.

ADVERTISING DISPLAY SIGN.

Application filed July 11, 1922. Serial No. 574,217.

To all whom it may concern:

Be it known that I, NORVIN J. STEINAU, a citizen of the United States, residing at Louisville, in the county of Jefferson and State of Kentucky, have invented certain new and useful Improvements in Advertising Display Signs, of which the following is a specification.

This invention has to do with an improved advertising display sign and method by which it is manufactured. It has reference particularly to an improved construction of display sign for use in windows and similar locations.

15 The main object of the present invention is to provide a display sign which when placed against the glass of a window will have an appearance very similar to that created by the attachment of letters and 20 other symbols to the face of the glass, as is frequently done, but which sign may be manufactured and put into place against the window at a very small cost as compared to the usual and ordinary cost of letters as 25 attached to a window in the manner which is customary and well known.

Another object of the invention is to provide a display sign which when in place against the glass will present a very attractive and artistic appearance, and one superior in many respects to the appearance of letters and symbols as previously attached to the window.

Another object of the invention is to provide a display sign of such construction that the outlines of the letters and other symbols themselves will be emphasized against the background as viewed by a person looking into the window from the outside. In this 40 connection, another object is to so design and construct the display sign as to take advantage of the usually darkened interior of the store or room so as to emphasize the symbols and letters of the display sign itself.

Another object of the invention is to provide a display sign which may be very easily and quickly attached to the window in a relatively permanent and secure manner.

More particularly, an object in this connection is to provide a sign of this character which can be directly attached to the glass pane by simply moistening the surface of the glass, so that the sign, by reason of its

gummed nature, will adhere directly to the window surface.

55

A further object of the invention in this connection is to provide an improved method of manufacturing the signs. It may be stated that, owing to the fact that the visible portion of the sign surface is peculiarly and 60 distinctively formed, special provision has been made for manufacturing the same, so that this peculiar and distinctive appearance may be retained, while at the same time providing the desired gummed character of the 65 surface.

55

Other objects and uses will appear from a detailed description of the invention, which consists in the features of construction and combinations of parts, as well as 70 steps of the process, as hereinafter described and claimed.

In the drawings:

Figure 1 shows a perspective view of a sheet of stock preparatory to the first step 75 of the process;

Fig. 2 shows a view similar to that of Figure 1, with the exception that the surface of the same has been coated with gum; or other adhesive material;

80

Fig. 3 shows a face view of the sheet of Fig. 2, with the exception that the gummed surface, after drying, has been printed with sizing or the like, according to the form of the letters and other objects which are to be 85 coated;

80

Fig. 4 is a view similar to that of Fig. 3, with the exception that gold or brass dust has been dusted over the surface so that it adheres only to those portions which were 90 printed with the sizing and is swept off of the remaining surface;

95

Fig. 5 is a view similar to that of Fig. 4, with the exception that the letters or other characters have been die-sunk;

Fig. 6 is a section taken on the line 6—6 of Fig. 5, looking in the direction of the arrows; and

95

Fig. 7 is a view similar to that of Fig. 5, with the exception that the blank has been 100 die-cut so as to bring its peripheral portion into proper harmony with the forms of the letters, and also to remove the material from certain of the central portions of the blank.

Referring first to Fig. 7, which shows 105 the completed article: The advertising dis-

play sign of the present invention comprises essentially a sheet of card board or paste board cut to the desired exterior configuration, and having its face portion cut and 5 ornamented in the proper manner to provide the desired display figures and symbols. The particular sign illustrated in the drawings is for "Business Boosters," and the exterior configuration of the sign is so cut that 10 the outlines of the upper portions of the letters are established by the configuration of the sign itself, and in like manner the outlines of the lower portions of the letters are similarly established by the configuration 15 of the sign itself. In addition to the foregoing, the outlines of any other figure, such as a can of coffee, are established by the contour of the sign itself.

The background of the sign is colored 20 generally a dark color, or black, as shown in the drawing. The outlines of the lower portions of the upper letters and of the upper portions of the lower letters are completed by the proper shaping of the background, 25 as is clearly evident from Fig. 7. Furthermore, the peripheral portions of the various letters or similar symbols are emphasized by relatively heavy outlines, such as shown at 8 and 9 in Fig. 7 for the letter B. Consequently, the central portions 30 of these letters stand out with greater clearness and emphasis. This effect is emphasized by making the peripheral portions of the letters either black to conform with the background, or of the same dark color as the 35 background if it be other than black.

The background of the sign and the peripheral portions of the various letters lie in a flat plane, so that, when the sign is applied 40 directly against the window pane, these portions will lie flush against the glass. On the contrary, the body portions of the letters are upset a very substantial distance, as shown in Fig. 6, so that, when the sign is set into place against the window pane, these body portions of the letters stand a considerable distance away from the glass. This form and construction of the sign is 45 readily produced by the proper upsetting or embossing operation, either simultaneously with the cutting of the outline contour or subsequently.

Furthermore, the central portions of the letters or symbols are colored a contrasting 55 color as compared to the background of the sign, so that the forms of these letters and symbols will stand out against the background of the sign with great emphasis and force. For example, in those cases in which 60 the background of the sign is black, the body portions of the letters and symbols may be advantageously made of gold or silver color, and this is the combination which it is contemplated will be most frequently used.

When the background of the sign is made black, and the body portions of the letters and symbols are of gold or silver, a very striking appearance is produced when the sign is set against the inside face of a window so as to be visible to persons on the outside. This is because the black background of the sign itself tends to merge with the relatively dark interior of the store or other room, and therefore the background 70 of the sign itself is not in evidence, but the observer has emphasized to his notice the gold or silver letters and other symbols in a forcible manner. Owing to the upsetting of the letters in the manner clearly illustrated in Fig. 6, and particularly in those cases in which this upsetting is of a beveled or V form, the shading of the two sides of the upset portion is emphasized, since the light striking the same is reflected in different directions. The result is that the sign presents an appearance strikingly similar to that created by the attachment of porcelain or other similar letters to the surface 80 of the window in the manner well understood and practiced heretofore.

The entire black surface of the center is provided with a gummed surface, so that upon moistening the window the sign may be readily applied thereto. In order to bring about this result, and at the same time provide a sign embodying the appearance and characteristics hereinbefore explained, the following steps or procedure may be resorted to: A relatively large blank of paste 90 board or other suitable stock is cut up into relatively small sections 11, as shown in Fig. 1. One surface of the blank is coated with black either before being cut up into small sections or afterwards, but in Fig. 1 105 I have not illustrated the top surface as being solid black, simply for convenience in illustration. The blanks are then coated on the black surface with a coating of gum or other adhesive 12, as shown in Fig. 2.

Figs. 3, 4, 5, 6 and 7 are face views of the succeeding steps of the process on somewhat larger scale than Figs. 1 and 2. After the gumming operation of Fig. 2, the desired characters or words are printed on the black 115 gummed surface by the use of sizing or other sticky material, so as to form the letters or objects shown in white in Fig. 3. While this sizing or other sticky material is still damp, the entire surface is dusted over with 120 either gold or brass or bronze dust or powder, or other dust or powder, such as aluminum, so that this material adheres only to those portions of the surface which are still sticky.

The blank is then subjected to a die-sinking operation so that each of the letters or other symbols is upset backwardly, as shown in Figs. 5 and 6. In the case of letters of brass or gold, this die-sinking operation 130

serves to provide a very distinctive appearance when viewed from directly in front.

Afterwards the blank may be cut out in its border and certain of its central portions, 5 so as to give the border a form substantially in harmony with the forms of the letters themselves, as shown in Fig. 7.

While I have herein shown and described only a particular form of sign embodying 10 the features of the present invention, and only a particular method of manufacturing the same, still I do not limit myself to this form and method, except as I may do so in the claims.

15 I claim:

1. As a new article of manufacture, an advertising display sign for use in conjunction with the surface of a window or the like, said sign being provided with advertising letters or other symbols, and said sign comprising a blank of material having its peripheral portion cut to the desired contour to establish the peripheries of the lower portions of the lower symbols and to establish the peripheries of the upper portions of the upper symbols, the body portion of each symbol being upset or embossed into V-shaped cross section, the peripheral portion of each symbol and the central portion 30 of the body of the sign being flat and adapted to lie in flush manner against the surface of the window, said flattened portions being black in color, and the upset portions of the symbol being of a brightly contrasting color, the flat surface of the sign being provided with a coating of gum material, whereby the sign may be attached in flat manner to the surface of a window, and whereby, 35 when the sign is in place against the sur-

face of the window, the black peripheral 40 portions of the symbols and of the body of the sign merge with a relatively darkened interior, and whereby the body portions of the symbols are emphasized to the observer, substantially as described. 45

2. As a new article of manufacture, an advertising display sign for use in conjunction with the surface of a window or the like, said sign being provided with letters or other symbols, and said sign comprising a blank of material having its peripheral portion cut to the desired contour to establish the peripheries of the lower portions of the symbols and to establish the peripheries of the upper portions of the symbols, the body portion of each symbol being upset or embossed into V-shaped cross section, the peripheral portion of each symbol and a portion of the central portion of the body of the sign being flat and adapted to lie in flush manner 50 against the surface of the window, said flattened portions being of a dark color, and the upset portions of the symbols being of a brightly contrasting color, and means for securing the sign to the surface of the window with its flat face lying flush against the window and with its upset portions projecting away from the surface of the window, comprising a coating of gum material 55 on the flat portions of the sign, whereby, when the sign is in place against the surface of the window, the relatively dark peripheral portions of the symbols and of the body of the sign merge with a relatively darkened interior, and whereby the body portions of 60 the symbols are emphasized to the observer, substantially as described. 65

NORVIN J. STEINAU.
